UNITED STATES PATENT OFFICE.

JAMES PATTERSON WILSON, OF LOS ANGELES, CALIFORNIA, ASSIGNOR TO WILL H. GROSSCUP, OF LOS ANGELES, CALIFORNIA.

RESILIENT CONNECTING DEVICE.

1,139,319.

Specification of Letters Patent. Patented May 11, 1915.

Application filed March 19, 1914. Serial No. 825,800.

To all whom it may concern:

Be it known that I, JAMES P. WILSON, a citizen of the United States, and a resident of Los Angeles, in the county of Los Angeles and State of California, have invented a new and Improved Resilient Connecting Device, of which the following is a full, clear, and exact description.

The invention relates to resilient means for connecting two members or articles such as for attaching suspender parts to trousers, or for use in or with garment supports, or trusses, or other articles of wear involving the yielding connection of two articles or members, or the attaching of one article to another, whereby the connecting means will be under tension.

The invention particularly relates to suspender ends, or to a similar flexible element returned on itself and having metallic coil springs around the same, to resiliently connect the said flexible element, whereby non-elastic flexible elements may be employed. The use of a continuous coil spring permits the cord to slide in the spring. In my invention, separate springs are employed on the flexible element, and a device is arranged between the springs at the U-bend of the element, the result being that the cord or like flexible element will be prevented from running through the springs by a pull on either end of said cord.

The invention will be particularly described as embodied in suspender ends.

Reference is to be had to the accompanying drawings forming a part of this specification, in which similar characters of reference indicate corresponding parts in all the views.

Figure 1 is a front elevation, with parts broken out and in section, showing my improved tension means applied to a known form of suspender ends and the lower portion of the webbing; Fig. 2 is a vertical section on the line 2-2 of Fig. 1; Fig. 3 is a cross section on the line 3-3 of Fig. 1; Fig. 4 is a plan view of a guard device employed in connection with the tension means in the form shown in Fig. 1; and Fig. 5 is a perspective view of the modified guard device that may be employed.

Referring particularly to Figs. 1 to 3, the webbing 10 of the suspender is upturned, as at 11, at the front of the webbing, to form a pocket between the said front and back.

The pocket is completed by stitching the upper end of the front 11, as at 10^a, to the main stretch 10 of the webbing, and also vertically along the sides as at 10^b.

In the closed bottom 12 of the pocket gromets 13 are secured. The gromets engage at the interior of the pocket 12 with an apertured reinforcing plate 14, to strengthen said bottom. The gromets 13 provide eyes for the passage of elongated members 15 of cord or like flexible material. The cord is return-bent to produce the members 15, and said members may constitute a suspender end, being continuous with each other at the interior of the pocket 12 and merging into a U-bend 15^a at their juncture. Surrounding the members 15 within the pocket are the separate helical compression springs 16, the lower ends of which seat on the gromets 13. In order to prevent the cord 15 from having a running movement through the springs, I provide a guard 17 above the upper ends of the springs adjacent to the said bend 15^a. Said guard, as best shown in Fig. 7, is in the form of an S, or equivalent shape to provide eyes 17^a which surround the respective members 15, the said guard at the junction between the eyes 17^a engaging the under side of the bend 15^a, whereby the guard is prevented from displacement. Any running movement of the cord through the spring 16 and guard 17 will be checked and arrested by the said guard, because that member 15 of the cord moving toward the guard will, through the gripping engagement of the spring, draw the said spring against the guard, crowding the convolutions of the spring and tightening the grip of the spring on the cord at the bend, at one side of the guard. The guard furthermore maintains the springs separated, and prevents the one from jamming and interfering with the other, so that the form of the springs is maintained at the U-bend of the cord. A further result obtained also by the provision of the guard 17, is that, should one member 15 be released when worn, as by the loss of a button holding the same, then the released member 15 will simply be gripped at the U-bend and prevented from running through the spring. Moreover, the constant running of a cord which is permitted by the use of a single spring, results in a severe wear on the cord, due to friction.

By the described arrangement, a pull downward on the members 15 will place the 5 springs 16 jointly under compression, and the reaction of the springs will maintain tension on the said members and on the webbing. In the compression and expansion of the springs the upper ends thereof will be maintained against distortion or interference with each other by the guard 17.

Having thus described my invention, I 10 claim as new and desire to secure by Letters Patent:

1. In a device of the character described, a pocket, a flexible element returned on itself, presenting two elongated members continuous with each other and movable through the bottom of the pocket, separate compression springs coiled around said members within the pocket, and a separating device in fixed position on said flexible element between the springs and immovable longitudinally of said element, said separating device being abutted by the adjacent ends of the springs, and said springs being seated on the bottom of the pocket.

2. A supporting device for an article of wearing apparel and means thereon to attach said device to an article of apparel, said means comprising a flexible element returned on itself presenting two elongated members, an element presenting a pocket through which said members may move lon-

gitudinally, separate compression springs on said elongated members yieldingly resisting longitudinal movement thereof, and a 35 separating device in fixed position on the flexible element between the springs and abutted by adjacent ends of the springs, the opposite ends of the springs bearing against the bottom of the pocket.

3. A supporting device for an article of wearing apparel and means thereon to attach said device to an article of apparel, said means comprising a flexible element returned on itself presenting two elongated 45 members, an element presenting a pocket through which said members may move longitudinally, separate compression springs on said elongated members yieldingly resisting longitudinal movement thereof said springs 50 being seated in said pocket, and a separating device in fixed position on the flexible element between the springs and abutted by adjacent ends of the springs, said separating device presenting eyes embracing the 55 flexible element and disposed at an angle to each other.

In testimony whereof I have signed my name to this specification in the presence of two subscribing witnesses.

JAMES PATTERSON WILSON.
